THIRD TO LOYD S. PIERCE, OF AUBURN, NEW YORK

GOLF PRACTISING APPARATUS

Application filed March 7, 1931. Serial No. 520,863.

This invention relates to a golf practising apparatus in which a golf ball is anchored to a suitable support for limited movement to and from a normal position of rest, and is 5 adapted to be driven from its normal position of rest and with any degree of force commonly employed in open golf courses by means of any one of the usual or special golf clubs for the purpose of acquiring experience in the 10 proper stance and swing of the club for various plays commonly practised on open courses.

The main object is to provide a simple, compact and efficient apparatus of this character 15 which is portable and may be installed and used within a relatively small floor or ground space as, for example, in relatively small rooms of homes and other buildings, or upon decks of water craft and analogous places 20 where space is afforded sufficient for the stance of the player and swing of the clubs.

Another object is to provide means, brought 25 into action by the operation of the ball or its support from its normal position, for indicating in yardage, or otherwise, the force of drive of the ball from its normal position.

Other objects and uses relating to the specific parts of the apparatus will be brought 30 out in the following description.

20 In the drawings:

Figure 1 is a top plan of a golf practise apparatus embodying the various features of the invention, in which a rotary indicator is 35 adapted to be operated by the movement of the ball-supporting means from its normal position, the base of the apparatus being provided with platforms at both ends for the accommodation of right hand and left hand drivers.

40 Figures 2, 3 and 4 are enlarged transverse vertical sectional views, partly broken away, taken respectively in the planes of lines 2—2, 3—3 and 4—4, Figure 1, the various parts being shown in their normal positions of rest.

45 Figure 5 is an enlarged detail sectional view taken in the plane of line 5—5, Figure 8.

Figure 6 is a detail sectional view taken in the plane of line 6—6, Figure 4.

50 Figure 7 is a detail sectional view taken in the plane of line 7—7, Figure 5.

Figure 8 is a horizontal sectional view on a reduced scale taken in the plane of line 8—8, Figure 4, looking downwardly.

Figure 9 is an enlarged transverse vertical sectional view taken in the plane of line 9—9, 55 Figure 8.

Figure 10 is an enlarged detail sectional view taken in the plane of line 10—10, Figure 8.

Figure 11 is an enlarged detail sectional 60 view taken in the plane of line 11—11, Figure 9, the rock-shaft being locked.

Figure 12 is an enlarged horizontal sectional view, partly in top plan, of a modified 65 form of indicator mechanism and portions of its driving means.

Figure 13 is an enlarged transverse vertical sectional view taken in the plane of line 13—13, Figure 12.

Figure 14 is an enlarged detail sectional 70 view taken in the plane of line 14—14, Figure 12.

As shown in Figures 1 to 11 inclusive, this 75 golf practising apparatus comprises an inverted box-like supporting frame or housing —1— preferably of rectangular form and having the lower edges of its four corners provided with feet —1'— adapted to rest upon a floor or other substantial horizontal support, said frame or housing, with the remaining parts of the apparatus therein, being portable for transportation from place to place.

This frame or housing is provided with a 80 substantially horizontal top wall —2— a distance above the lower edge thereof corresponding to the height of an ordinary step of a staircase to permit the player to easily step from the floor support to said platform which is preferably rectangular and of sufficient 85 length and width to accommodate a player at either side of the transverse center thereof as may be necessary for right hand and left hand drivers, thereby forming two platforms —2'— of similar area.

The platform —2— is provided with a transverse elongated opening —3— substantially midway between the ends thereof and preferably near its front edge for receiving and permitting the operation of a 90 95 100

ball-supporting anchorage, presently described.

A mat —4— of relatively small area is adhesively or otherwise secured to the upper surface of the platform —2— to extend from the rear edge of the platform to a point in proximity to the rear end of the opening —3— and between the platforms —2'—, as shown in Figures 1 and 2.

The remaining portions of the upper surface of the platform —2— are covered with a felt or equivalent facing —5— in imitation of a grass plot, the pad —4— being extended upwardly slightly above the level of the felt facing —5— in imitation of a thicker grass plot or section directly at the rear of the normal position of the ball, as shown more clearly in Figures 2 and 9.

A resilient golf ball —6— is mounted upon one end of a suitable anchoring device consisting, in this instance, of a rocker arm —7— having its other end secured to a rock shaft —8— which is journaled in suitable uprights —9— of a supporting frame —10— within the housing —1— to rock about a horizontal axis lengthwise of the platform —2—.

That is, the rock shaft —8— is journaled in the uprights —9— in a plane some distance below the platform —2— within the housing —1— and is provided with the radially extending rock arm —7— carrying at its free end the ball —6— which, together with the rock arm, are movable about the axis of the shaft —8— within the opening —3— in the platform —2— to and from a normal position of rest.

The rock arm —7— normally extends upwardly from the shaft —8— through the opening —3— and above the platform —2— for supporting the ball —6— slightly above the upper surface of the members —4— and —5— so as to normally incline rearwardly from a vertical position against an adjustable stop —11— consisting, in this instance, of a screw engaged in an extension —12— of the upright —9—, as shown in Figure 2, for limiting the rearward movement of the rock arm —7— and permitting its free forward movement from the limiting stop when operated forwardly by a golf club or equivalent device from its normal position.

As previously intimated the anchored ball —6— is adapted to be driven forwardly with varying degrees of force, commonly used in open golf links or ranges, from its upright normal position of rest, shown by full lines in Figure 2, to approximately the position shown by dotted lines in the same figure, or through an arc of ninety degrees, more or less.

This operation affords practical experience in obtaining the proper stance of the operator and driving of the ball and constitutes one of the essential features of the invention, but it is desirable to provide some means for indicating the relative forces of the drive

of the ball at each play in linear measurement such, for example, as yardage commonly used in open course golf-playing for indicating the distance to which the ball has been driven.

Driving force indicating means

For this latter purpose a plunger —13— is movable vertically in a guide bracket —14— on the frame —1—, and has its upper end normally disposed in a plane slightly above the horizontal plane of the axis of the shaft —8— and in the path of movement of the ball —6— so that when the ball is driven forwardly and downwardly from its normal position about the axis of the shaft —8—, it will engage and depress the plunger —13— against the action of a spring —15— which tends to urge the plunger upwardly.

The lower end of the plunger is provided with a limiting stop or nut —16— adapted to engage the lower face of the guide bracket —14— for limiting the upward movement of the plunger by the spring —15—, as shown more clearly in Figure 5.

The spring —15— is secured at its lower end to the frame —10— by means of a screw —17—, and has its upper end secured to a radial pin —18— projecting forwardly from the front face of the plunger —13— through a vertical guide slot —19— in the bracket —14—, as shown more clearly in Figures 5 and 7.

A horizontal rotary shaft —20— is journaled in suitable bearings on the frame —10— between the plunger —13— and front side of the machine to extend transversely of the frame, preferably in a plane below the upper face of said plunger when the latter is its uppermost position.

A circular drum or disk —21— is secured to the shaft to rotate therewith in the plane of movement of the plunger —13— and is provided with a plurality of, in this instance two, diametrically opposite radial shoulders —22— projecting from the periphery thereof, one of said shoulders nearest the plunger being disposed in the path of a pawl —23— which is pivoted at —23'— to the upper end of the plunger and is free to swing downwardly and inwardly toward the axis of the plunger, but is held against outward and upward swinging movement from a normal position by engagement with the top wall of a slot in the plunger, as shown more clearly in Figure 2, said pawl being provided with a weighted member —24— for returning it to its normal position.

It is now evident that when the ball is driven forwardly and downwardly with any degree of force, it will engage and depress the plunger —13— against the action of its retracting spring —15—, thereby causing the pawl —23— to engage the adjacent shoulder —22— and rotate the disk —21— and its supporting shaft —20—, under which condi-

tions the pawl —23— will be carried downwardly beyond and out of the path of movement of the shoulder —22—, thus permitting free rotation of the disk —21— and its shaft —20— any number of turns under its own momentum according to the force of impact of the ball upon the upper end of the plunger.

Suitable means is provided for locking the plunger —13— in its extreme down position to which it has been driven by the impact of the ball therewith and for this purpose an upright lever —25— is pivoted intermediate its ends at —25'— to a post —26— on one side of the bracket —14— of the frame —10— and has its lower end normally spring-pressed outwardly by means of a leaf spring —27—, the upper end of said lever being provided with a pivoted pin —28— guided in an opening —28'— in the adjacent side of the bracket —14— and adapted to enter a socket —29— in the adjacent side of the plunger —13— when the latter is depressed by the pawl to the limit of its downward movement. See Figures 5 and 7.

That is, when the plunger —13— is driven downwardly by the impact of the ball therewith, the lever —25— will be operated by the spring —27— to force the locking pin —28— into the registering socket —29— in said plunger to hold the latter against upward return movement, and thus permit free rotation of the disk or drum —21— and its shaft —20— until the lever —25— is tripped, in a manner presently described, but after the drum —21— has ceased its rotation under its own momentum.

Suitable means is also provided for locking the ball —6— and its supporting arm —7— in its extreme down position, shown by dotted lines in Figures 2 and 9, to which it has been driven by the player, and for this purpose the shaft —8— is provided with a radial peripheral socket —30— adapted to receive a locking pawl —31— which is guided in a supporting member —32— on the frame —10— and is normally urged toward the periphery of the shaft by a coil spring —33—, as shown more clearly in Figures 4, 9 and 11.

It is now clear that when the ball —6— and plunger —13— have been driven downwardly and locked in their down positions in a manner described, the disk or drum —21— and shaft —20— will have been set in motion to rotate under their own momentum a number of turns corresponding to the force of drive.

The platform —2— is provided with a sight-opening —21'— registering with the upper central portion of the periphery of the underlying drum 40 to permit reading of the yardage scale on said drum, see Figures 1 and 6.

Suitable means actuated by the shaft —20— is provided for indicating, preferably

in linear measurement such as yardage, the force of drive of the ball from its normal position. For this purpose, the shaft —20— is provided with a worm —34— meshing with a worm gear —35— which is loosely mounted upon a shaft —36—.

A clutch —37— is splined upon the shaft —36— to rotate therewith and is operable axially into and out of engagement with the gear —35— by means of a shifting lever —38— so that when the clutch is engaged, rotary motion will be transmitted from the shaft —34— to the shaft —36—. (See Figs. 3, 6, 8 and 9.)

This shaft —36— is journaled in suitable bearings —39— in the frame —10— and front wall of the housing —1— and serves to receive and support an index wheel —40— rotatable therewith and provided upon its periphery with a scale —41— representing gradually increasing yardage from zero to three hundred, but obviously the graduations may represent other units, if desired.

The lever —38— is operated by means of a spring —38'— to normally hold the clutch —37— in engagement with the gear —35— but may be tripped from its holding position at will by means of a cam rod —42— which is guided in an opening in the central front portion of the platform —2—, and is provided at its upper end with a pedal —42'— by which it may be depressed by the operator into engagement with the upper end of the lever —38— against the action of a retracting spring —43— for releasing the clutch —37—. (See Figs. 1, 3, 8 and 9.)

When the clutch —37— is released in the manner just described, the indicator wheel —40— will be restored to its starting position by a weighted cord —44— having one end attached to the periphery of the hub of said indicator wheel and its other end provided with a weight —44'— capable of restoring the wheel to its starting position until limited by the engagement of the cooperative stops —45— and —45'— on the wheel —40— and frame —1— respectively. See Figures 3 and 6.

It is now evident that when the shaft —36— is rotated by its driving shaft —34— due to the impact of the ball —6— against the plunger —13—, the weighted cable —44— will be wound upon the hub of the wheel —40—, which is of sufficient circumferential length to record the yardage produced by the maximum force of drive of the ball against the plunger —13— during slightly less than one complete revolution of said wheel.

In other words the gear ratio between the drive shaft —34— and driven shaft —36— for the indicator wheel is such as to permit the driving shaft to rotate a relatively large number of turns to effect a single revolution of the indicator wheel.

It is desirable to provide means for positioning one or the other of the shoulders 22 on the disk 21 to bring such shoulder into position to be engaged by the pawl 23 when the plunger is restored to its normal up position.

To this end the shaft 20 is provided with diametrically opposite cam members 46 having their outer ends pointed and disposed in substantially the same plane as the shoulders 22, as shown more clearly in Figures 4 and 9.

The shaft 20 is also provided with an eccentric weight 47 projecting radially therefrom to one side thereof at an angle of about forty-five degrees to the plane of the shoulders 22 and cam members 46, as shown more clearly in Figure 4, so that when the disk 21 reaches the end of its rotation under its own momentum the weighted member 47 will automatically rotate the disk until the shoulders 22 and cam points 46 stand at an angle of substantially forty-five degrees to a horizontal plane through the axis of the shaft, thus bringing one of the cam points 46 below the horizontal plane of the shaft, or into the path of the front end of a forwardly and rearwardly movable slide rod 49, shown more clearly in Figures 4 and 9.

This slide rod 49 is movable endwise in spaced bearing members 50 on the frame 10 transversely of, and in a plane slightly below, the shaft 20 and is normally withdrawn rearwardly out of the path of the rotating cam members 46 by means of a spring 51, Figures 4 and 9.

When the disk 21 and its supporting shaft 20 assume their normal positions of rest through the action of the weight 47, one of the cam members 46 will be disposed in the path of movement of the front end of the slide rod 49 so that when the latter is moved forwardly, in a manner presently described, it will engage the registering cam member 46 and thereby rock the shaft 20 and its disk 21 in a counter clockwise direction, Figure 9, until the rearmost shoulder 22 is brought into position to be engaged by the pawl 23 on the plunger 13 when the latter is released and restored to its uppermost position.

The means for moving the slide rod 49 forwardly to effect the last-named operation of the disk 21 comprises a crank-arm 52 secured to a rock shaft 53 which is journaled in suitable bearings in the frame 10 and has its upper end engaging in a slot 52' in the slide rod 49, as shown in Figure 9. The shaft 53 extends lengthwise of the machine parallel with, and in a plane below, the shaft 20 and is provided at one end with an additional crank-arm 54 to which is connected the lower end of an upright rod 55 which extends

upwardly through a guide opening in the top of the frame 1 and is provided at its upper end with a pedal 56 by which it may be depressed from its normal up position to the position shown by dotted lines in Figure 4 for rocking the shaft 53 and thereby causing the crank-arm 52 to move the slide rod 49 forwardly against the action of the spring 51, as shown in Figures 2, 4, 8 and 9.

One end of the spring 51 is connected to one of the upright brackets of the frame 10 and has its other end connected to a block 57 which is secured to the slide rod 49, as shown more clearly in Figure 9, said block being guided on the frame 10 to hold the slide rod 49 against rotary movement, as shown in Figures 2, 4, 8 and 9.

A suitable collar 58 is secured to the slide rod 49 to engage the front face of one of the uprights of the frame 10 for limiting the rearward movement of the slide rod from its forward position shown by full lines in Figure 9 to the position shown by dotted lines in the same figure. (See Fig. 4).

This forward movement of the slide rod 49 is also utilized for releasing the locking pin 28 from holding engagement with the plunger 13 to allow the latter to be restored to the uppermost position by its spring 15, and for this purpose the block 57 is provided with a cam plate 60 having its forward end pointed, as shown more clearly in Figure 7, and adapted to wedge against the outer edge of the lower end of the lever 25 for forcing the same inwardly against the action of the spring 27, thereby forcing the upper end of the lever 25 outwardly to withdraw the locking pin 28 from engagement in the socket 29 in the plunger 13, and allow said plunger to be restored to its upward position by the spring 15 simultaneously with the forward movement of the slide rod 49.

As the plunger 13 is moved upwardly its pawl 23 rides against the outer edge of the adjacent shoulder 22 of the disk 21, at which time the shoulder 22 will be in position to be engaged by the pawl as the latter is actuated to its holding position by the counterweight 24, it being understood that the weight 47 on the shaft 20 will yieldingly hold the shoulder 22 in engagement with the pawl 23. See Figures 2, 4, 8 and 9.

The forward movement of the slide rod 49 is also utilized for releasing the holding pawl 31 from engagement with the rock shaft 8 carrying the pawl-supporting member 7 and for this purpose the rear end of the slide rod 49 is provided with a radially projecting arm 61 carrying a cam plate 62 having its forward

end tapered or pointed to pass between the lower face of the rock shaft —8— and holding pawl —31— to force the latter out of the socket —13— in the rock shaft —8—, as shown in Figures 9 and 10, and thus permit 5 the ball-supporting member —7— with the ball thereon to be returned to its upward rearwardly inclined position against the limiting stop —11—, as shown by full lines in Figures 2 and 9.

10 As shown more clearly in Figure 10, the arm —61— on the rear end of the slide rod —49— is provided with a forwardly projecting member —63— adapted to engage a radial pin —64— on the rock shaft —8— immediately following the tripping of the pawl —31— for positively restoring the rock shaft —8— and ball-supporting member —7— carried thereby to their normal starting positions with the ball-supporting member —7— 15 in an upwardly and rearwardly inclined position against its limiting stop —11—, thus completing the cycle of operation for one play. (See Figs. 4, 9 and 11).

The construction shown in Figures 12 to 25 14 inclusive is quite similar to that set forth in Figures 1 to 11 inclusive, except that the worm wheel —35— driven by the shaft —20— is secured to a shaft —36'— having a threaded extension or screw —65— upon 30 which is mounted a collar —66—.

This collar is slidable lengthwise over and upon the screw extension —65— and is provided with a pin —67— mounted upon a hand lever —69— which is pivoted at —68— to the collar —66— and is spring-pressed in 35 one direction for yieldingly holding the pin —67— in engagement with the threads of the extension —65— Figure 13.

40 The threaded extension —65— of the shaft —36'— is enclosed in a suitable housing —70— having one end bolted or otherwise secured to the front upright wall of the main frame or housing to extend forwardly therefrom and its other end provided with a bearing —70'— in which the adjacent end of the screw shaft —65— is journaled. This housing —70— is provided with a top plate —71— extending the entire length thereof 45 and provided with a central lengthwise slot —72— through which the hand lever —69— extends so as to move lengthwise thereof as the collar —66— with the lever —69— thereon is moved axially of the screw shaft —65— 50 by the engagement of the pin —67— therewith as the shaft is rotated, it being understood that the walls of the slot —72— cooperate with the lever —69— to hold the collar —66— against relative turning movement upon the shaft —65—.

55 The hand lever —69— is returned rearwardly into close proximity to the upper face of the plate —71— to form a pointer —69'— which is movable along suitable scales 60 —73— on the upper face of the plate —71—

when the collar —66— is actuated by the rotation of the screw shaft —65—.

These scales —73— are arranged at opposite sides of the slot —72— and indicate linear measurement, preferably in yards, representing the force of drive of the ball —6— from its normal position of rest, as shown in Figures 2, 4 and 9. It is now evident that when the ball 6 and its supporting member 7 is driven from its normal position, it will engage and depress the plunger —13— against the action of its retracting spring —15— until locked in its down position by the pin —28—.

This operation of the plunger carrying the pawl —23— causes the rotation of the disk —21— and shaft —20— thereby rotating the screw shaft —65— through the medium of the worm and gear —34— and —35—.

This rotation of the shaft —65— causes the collar —66— to travel along said shaft a distance corresponding to the force with which the plunger —13— has been depressed by the impact of the ball —6— therewith, the distance being indicated on the scales 90 —73— by the pointer —69'—.

The screw shaft —65— and its housing —70— are shown as disposed in a substantially horizontal plane forwardly of the main frame —1—, so that the scales —73— and pointer —69'— are readily visible to the player while standing upon the main frame but obviously, may be placed at any suitable angle about the axis of the shaft —20— relatively to the main frame —1—, without departing from the spirit of the invention.

When the screw shaft —65— has ceased its rotation under its own momentum produced by the impact of the ball against the plunger —13— resulting in a movement of the collar —66— and pointer —69'— from its normal position adjacent the main frame, the hand lever —69— may be rocked downwardly about its pivot —68— to withdraw the pin —67— from engagement with the screw shaft —65—, thus permitting the collar —66— to be returned along the shaft to its starting position by means of the hand lever —69—.

The construction and operation of both forms of our invention, have now been clearly and fully described, but obviously various changes may be made in the detail construction and operation, without departing from the spirit of the invention.

What we claim is:—

In a golf practise apparatus, a rocker-arm movable about a fixed axis to and from a normal position of rest and provided with a ball adapted to be driven in one direction from its normal position by means of a golf club, a movable member in the path of the driven ball and actuated thereby, a rotary element, means for transmitting motion from said movable member to the rotary element to cause the latter to rotate and to continue its 125 130

rotation under its own momentum, a movable indicator, means for transmitting motion from the rotary element to the indicator, and releasable means for locking the rocker-arm in its driven position.

5 In witness whereof we have hereunto set our hands this 25th day of February, 1981.
